UNITED STATES PATENT OFFICE.

WILLIAM L. CASPER, OF BROOKLYN, NEW YORK, ASSIGNOR TO WESTERN ELECTRIC COMPANY, INCORPORATED, OF NEW YORK, N. Y., A CORPORATION OF NEW YORK.

TRANSFORMER.

Application filed October 19, 1922, Serial No. 595,538.

To all whom it may concern:

Be it known that I, WILLIAM L. CASPER, a citizen of the United States, residing at Brooklyn, in the county of Kings, State of New York, have invented certain new and useful Improvements in Transformers, of which the following is a full, clear, concise, and exact description.

This invention relates to transformers and particularly to balanced transformer circuits.

An object of this invention is to provide means for eliminating unbalanced capacity effects in a transformer.

Another object of this invention is to provide a transformer which may be introduced into a signaling circuit without disturbing the balanced relation of the two sides of the signaling circuit with respect to ground.

In accordance with the form of this invention hereinafter described in detail, the unbalanced capacity effects between the various parts of a transformer are eliminated by surrounding the core of the transformer with a split shield, each half of the shield being electrically connected to one wire of a twisted pair which forms the transformer winding adjacent the core. This arrangement serves to remove unbalanced electrostatic capacity effects which would otherwise destroy the symmetrical distribution of the capacities of the various windings of the transformer with respect to the line wires of the signaling circuit and ground. This type of transformer is particularly useful in phantom circuits where a high degree of balance is necessary.

The drawing illustrates this invention embodied in an auto-transformer which may be employed for interconnecting signaling or telephone lines of different impedances.

Fig. 1 shows diagrammatically the method of connecting the various coils. Fig. 2 is a diagrammatic plan view of the transformer.

Referring to the drawing in which the same reference numerals are used in both figures, 8 represents a transformer core of any desired construction, which may be toroidal for example. Surrounding the core 8 is a split metallic shield, the two halves 9 and 10 being insulated from each other and from the core. Windings 11 and 12 represent wires which may be wound in a plurality of layers around the shield 9 and 10 as a twisted pair. While the windings

11 and 12 as well as the other windings are multilayer windings they are shown in Fig. 2 as single layer windings, so as to avoid confusion. Windings 13 and 14 are superposed upon the twisted pair 11 and 12, winding 13 being wound on one half of the core and winding 14 on the other half. Windings 15 and 16 are then wound on the core, winding 15 being superposed on winding 14 and winding 16 being superposed on winding 13. Conductors 17 and 18 represent a section of a signaling circuit connected to the outer terminals of windings 15 and 16, while conductors 19 and 20 represent a second section of a signaling circuit connected to intermediate points of the auto-transformer. The letters "i" and "o" have been applied to various parts of the transformer windings to indicate which part is the inner layer of the winding or the outer layer of the winding, the letter "i" representing the inner layers and the letter "o" representing the outer layers. Windings 14 and 16 are wound in opposite directions from windings 15, 13, 11, and 12. Windings 15, 13, 11, 12, 14 and 16 are connected in series aiding to a current passing from line 17 to line 18 through these impedances in the order named.

The various capacities shown in the drawing in dotted lines represent the natural capacity effects existing between adjacent windings, between the windings and the transformer casing 22 and between the windings and the split shield 9, 10.

Capacity 23, which represents the natural capacity between the outer layer of winding 15 and casing 22, is symmetrically situated in the circuit with the capacity 24 between the casing and the outer layer of winding 16, so that these two capacities do not unbalance the transformer with respect to the two sides of the signaling circuit, which are required to be maintained at equal potentials above ground. The following capacities are symmetrically located with respect to the two sides of the signaling circuit and consequently do not tend to unbalance the transformer; capacity 25 between the outer layer of winding 14 and the inner layer of winding 15; capacity 26 between the outer layer of winding 13 and the inner layer of winding 16; capacity 27 between the outer layer of winding 11 and the inner layer of winding 14. Capacity 28, between the outer layer of winding 12 and the inner

layer of winding 13, is balanced by capacity 29 between the outer layer of winding 12 and the inner layer of winding 14, since these two capacities are effectively connected in shunt respectively, to windings 11 and 12. Capacity 40 is unsymmetrically placed but short circuited. Capacity 30 between the outer layers of the twisted pair 11 and 12, is effectively balanced by capacity 31 between the inner layers of the twisted pair. There is capacity between the two wires of the twisted pair through this length. For clearness the capacity located only at the ends of the windings has been shown. It is evident that for each element of this capacity located on one side of the neutral point of the windings, there is one equal element on the other side symmetrically placed. Capacity 32 between the inner layer of winding 11 and the shield 9, is effectively shunted around winding 11 by connecting wire 33, which directly connects the outer layer of winding 11 to the shield 9. Similarly, capacity 34, between the inner layer of winding 12 and the shield 10, is effectively shunted around winding 12 by a connecting wire 35, which electrically connects shield 10 to the outer layer of winding 12. The capacities 32 and 34, therefore, are balanced against each other. The capacity effect 36, from the inner layer of winding 11 and the shield 10, is short-circuited by the connecting wire 35 just mentioned. A corresponding capacity 37, between the inner layer of winding 12 and shield 9, is connected around both windings 11 and 12 by the connecting wire 33, and the capacity 37 is, therefore, symmetrically situated with respect to the two sides of the signaling circuit.

From the above description it follows that the natural capacity effects existing between the various parts of the winding, the windings and the casing, and the windings and the core, are so located that they counterbalance each other, or are symmetrically located with respect to the two sides of the line or are short-circuited. The resulting transformer is, therefore, of particular importance in signaling circuits such as telephone circuits, since its introduction into the circuit will not disturb the balance of the signaling line. The importance of maintaining the two wires of a signal line balanced with respect to ground, is due to the possible cross-talk effects which may take place between the given circuit and neighboring circuits whenever any capacity unbalance exists and more particularly when that circuit is used as a side circuit to the possible cross-talk effects between the phantom circuit and the side circuit.

In the above described transformer arrangement, windings 11 and 12, which form a twisted pair, will, of course, be composed

of an equal number of turns. In order to obtain an exact balancing of the capacity effects, winding 13 should be composed of the same number of turns as winding 14, and winding 15 should be composed of the same number of turns as winding 16. It will also be found advisable to balance the d. c. resistances of the series of the windings.

It is to be understood that various modifications of the above-described transformer arrangement may be made without departing in any wise from the spirit of this invention as defined in the appended claims. This invention, for example, is not limited in its utility to auto-transformers, but may be applied to other types of inductance elements or other electrical devices composed of a plurality of windings arranged on a common core.

This invention claimed is:

1. A transformer comprising a core, a winding on said core wound in a plurality of layers, said transformer having a natural capacity between a layer of said winding and another part of said transformer, which capacity is unsymmetrically located with respect to the external terminals of said transformer, and means comprising a shield surrounding a portion of said core for symmetrically locating said capacity with respect to said external terminals.

2. A transformer comprising a core, a winding on said core wound in a plurality of layers, said transformer having a natural capacity between a layer of said winding and said core, and means for short-circuiting said capacity.

3. A transformer having a core, a shield surrounding said core and comprising a plurality of insulated sections, a winding surrounding said shield, and connections from different points on said winding to different sections of said shield.

4. An inductance device comprising a shield of a plurality of insulated sections, a winding surrounding said shield, and a connection from each of a plurality of said sections to said winding.

5. A transformer comprising a core, a shield surrounding said core of a plurality of insulated sections, a winding of a plurality of layers around said shield, said transformer having a natural capacity between said shield and the adjacent layer of said winding, and a connection between another layer of said winding and said shield.

6. An inductance device comprising a core, a shield surrounding said core, a winding around said shield, and a connection between said shield and said winding to symmetrically connect with respect to the external terminals of said device the natural capacity between said shield and the inner layer of said winding.

7. A transformer comprising a plurality

of windings each comprising a plurality of layers and having a common terminal, a magnetic core, a shield between said core and said windings, and a connection from said shield to the outer layer of one winding to short-circuit the capacity between said shield and the inner layer of said other winding.

8. A transformer comprising a core, a plurality of windings around said core, a casing surrounding said windings, and means comprising an electrostatic shield surrounding said core and comprising a plurality of insulated sections for causing said transformer to be electrostatically balanced.

15 9. A transformer comprising a core, a shield with a plurality of sections around said core, a twisted pair of wires wound in a plurality of layers surrounding said shield, and a direct connection from the outer layer 20 of each of said wires to a portion of said shield.

10. A transformer comprising a core, a plurality of windings surrounding said core,

and means for preventing an electrostatic unbalance between said core and said windings. 25

11. A transformer comprising a metallic casing and an electrostatically balanced winding comprising four multi-layer sections, two of which sections are wound on one portion of the core and the other two 30 on another portion of the core said sections being serially connected in the following order: the inner layer of the outer section on one part of said core to the outer layer of the inner section on the other part of said core, 35 the inner layer of said last mentioned section to the inner layer of the other inner section and the outer layer of said last mentioned inner section to the inner layer of the other outer section, said two last mentioned sections being wound in the opposite direction to said two first mentioned sections. 40

In witness whereof, I hereunto subscribe my name this 17th day of October A. D., 1922.

WILLIAM L. CASPER.
